UNITED STATES PATENT OFFICE.

ALONZO W. EPRIGHT, OF ALTOONA, PENNSYLVANIA.

CAR-WEIGHING APPARATUS.

1,142,407.

Specification of Letters Patent.

Patented June 8, 1915.

Application filed April 27, 1915. Serial No. 24,223.

To all whom it may concern:

Be it known that I, ALONZO W. EPRIGHT, a citizen of the United States of America, residing in Altoona, in the county of Blair, 5 State of Pennsylvania, have invented certain new and useful Improvements in Car-Weighing Apparatus, of which the following is a true and exact description, reference being had to the accompanying drawings, which form a part thereof.

My present invention relates to apparatus for weighing railway cars while in motion, and is an improvement on the apparatus for this purpose covered by my prior 15 Patent No. 956,323 issued April 26, 1910. In the apparatus disclosed in my prior patent, the track over which the cars are passed to the railroad scale is formed with a hump comprising two inclined sections 20 meeting at an apex located at a definite, though adjustable elevation, and at a definite distance from the adjacent edge of the scale platform. The purpose of this hump is to deliver cars of different lengths, pushed 25 over the hump and approaching the latter with the same velocity, onto the scale platform with velocities which are higher in the case of cars having relatively short wheel bases than in the case of cars having 30 relatively long wheel bases. The hump thus automatically equalizes the available weighing periods for cars of different lengths approaching the hump at the same velocity. The hump arrangement of my prior patent 35 has been extensively used and has proved to be of great value for the rapid and accurate weighing of cars in motion. Some difficulty has been experienced in its use, however, from the fact that when the apex 40 of the hump is vertically adjusted, as it needs to be from time to time as the operating conditions change, the corresponding tendency to vary the acceleration of the front end of the car passing over the hump, 45 is offset to some extent by the variation in the resistance to the upward movement of the rear truck of the car. The relation between the tendency to increased or decreased acceleration, and the increase or decrease in 50 resistance varies with the length of wheel base of the car, and introduces an uncertainty in operation, and it is the object of the present invention to avoid this variable resistance to movement of the rear wheels 55 of a car during the period in which the velocity of the car should accelerate.

The means which I have devised for accomplishing my object comprises a hump divided into three sections of which the intermediate section is at the top of the hump 60 and is preferably horizontal, or substantially so, and the end sections are downwardly inclined from the ends of the intermediate section, and in which the intermediate section may be maintained substantially parallel to itself in its different 65 adjustments.

The various features of novelty which characterize my invention are pointed out with particularity in the claims annexed 70 to, and forming a part of this specification.

For a better understanding of the invention, however, and of the advantages possessed by it, reference should be had to the accompanying drawings and descriptive 75 matter in which I have illustrated and described the preferred embodiment of my invention.

Of the drawings: Figure 1 is a diagrammatic elevation illustrating a railway track 80 scale with my improved hump in the track leading thereto; Fig. 2 is a partial longitudinal section through a portion of the hump; and Fig. 3 is a section on the line 3—3 of Fig. 2.

In the drawings: A represents the scale and B the wall of the scale pit, the bottom of the latter being shown as horizontal.

C is the track section supported by the scale platform; C', C² and C³ the three 90 track sections forming the hump in the track over which the cars are passed to the scale.

In the particular construction illustrated, the track rails C⁴, proper, pertaining to the hump structure are supported on chairs F 95 which in turn are mounted on the usual cross ties G. The cross ties G for the hump section C' are supported on the upper edges of beams H' which, in the form shown, are built up beams made of rolled metal shapes 100 and tied together by cross braces I; similarly the cross ties G for the hump sections C² and C³ are supported on the pairs of brace connected beams H² and H³ respectively. The lower ends of the beams H' of 105 the hump section C' are pivotally supported at J through hinge members J' and J², the hinge members J' being connected to the beams H, and the hinge members J² being supported by abutments B' raising from the 110 bottom of the extension of the scale pit B. The lower end of the hump section C³ is

similarly hinge supported on abutments B⁴ similar to abutments B'. The upper ends of the beams H' and the adjacent ends of the beams H² rest upon an adjustable support D and are mounted on abutments B² which, as shown, is a built up beam. Similarly the upper ends of the beams H³ and the adjacent ends of the beams H² rest upon an adjustable support DA which may be similar to 5 the support D, and is mounted on a corresponding pair of abutments B³. Any suitable provisions may be made for effecting the vertical adjustment of the supports D and DA to thereby vary the vertical elevation 10 of the hump section C². The means shown for this purpose comprise spacers D³ interposed between the enlarged end portions D' of the beams D and DA, and the subjacent abutments B² or B³, these spacers 15 being varied in number, or being replaced by others of different thickness in order to give the desired vertical adjustments of the ends of the hump section C². As shown, the beams D and DA are provided with ears D⁴ 20 under which tops of jacks, not shown, may be placed in order to raise and lower the beam to permit the spacing blocks D³ to be adjusted.

B⁵ represent seats provided for the lower 30 ends of the lifting jacks. The ends of the track rails C⁴ adjacent the scale platform may be supported on stationary cross beams K and K'. As shown the chairs F project through apertures M' in a stationary platform M which is carried by suitable beams L.

In the practical use of my invention for handling ordinary freight cars of the general character used in the standard railway practice in this country, the hump sections 40 C', C² and C³ may well be approximately twenty-five, twelve and sixteen feet in length respectively. It is to be understood, of course, that these dimensions are given primarily for illustrative purposes and may be 45 varied without departing from the spirit of my invention.

In the use of the invention the cars are pushed over the hump, and each car ordinarily begins to accelerate and thereby 50 breaks away from the section of the train back of it and from which it has previously

been uncoupled, at about the instant at which the rear truck passes onto the section C² of the hump, and in consequence the retarding force, varying with the vertical adjustment of the 55 hump apex, exerted by the hump section C³ on the rear truck of each car passing over the hump, need not affect the velocity with which the car moves off of the hump section C' and C² onto the scale. In the different vertical adjustments of the hump the intermediate section is ordinarily maintained horizontal or substantially so.

While in accordance with the provisions of the statutes I have illustrated and described the best form of my invention now known to me, it will be apparent to those skilled in the art that changes may be made in the form of apparatus disclosed without departing from the spirit of my invention and that 60 in some cases some features of my invention may be used without a corresponding use of other features.

Having now described my invention, what I claim as new and desire to secure by Letters Patent, is:

1. Car weighing apparatus comprising a track scale, a track leading thereto, and comprising an adjustable hump formed of an intermediate section, a downwardly inclined 80 section leading toward the scale from one end of said intermediate section, and another downwardly inclined section extending away from the opposite end of said intermediate section, and means for vertically 85 adjusting said intermediate section and the adjacent ends of said inclined sections.

2. Car weighing apparatus comprising a track scale, a track leading thereto, and comprising an adjustable hump formed of an intermediate and substantially horizontal section, a downwardly inclined section leading toward the scale from one end of said intermediate section, and another downwardly inclined section extending away from the opposite end of said intermediate section, and means for simultaneously effecting a vertical adjustment of each end of said intermediate section and the adjacent end of the adjacent inclined sections.

ALONZO W. EPRIGHT.
